WHEELED FIGURE TOY

Eugene Buhler, Cliffside Park, N. J.

Application November 21, 1949, Serial No. 6,173

Term of patent 3½ years

(Cl. D34—15)

To all whom it may concern:

Be it known that I, Eugene Buhler, a citizen of the United States, residing in Cliffside Park, county of Bergen, State of New Jersey, have invented a new, original, and ornamental Design for a Wheeled Figure Toy, of which the following is a specification, reference being had to the accompanying drawing, forming part thereof, and in which

Figure 1 is a front view of the wheeled figure toy showing my new design;

Figure 2 is a side view with the near wheel removed; and

Figure 3 is a top plan view of the toy.

I claim:

The ornamental design for a wheeled figure toy, as shown.

EUGENE BUHLER.
